UNITED STATES PATENT OFFICE.

GEORGE D. HOUSTON, OF RUSHVILLE, ILLINOIS.

FOOT PRESSURE-DISTRIBUTER FOR TWO-ROW CULTIVATORS.

1,281,963.

Specification of Letters Patent. Patented Oct. 15, 1918.

Application filed January 4, 1918. Serial No. 210,387.

To all whom it may concern:

Be it known that I, GEORGE D. HOUSTON, a citizen of the United States, residing at Rushville, in the county of Schuyler and 5 State of Illinois, have invented certain new and useful Improvements in Foot Pressure-Distributors for Two-Row Cultivators, as set forth in the annexed specification.

This invention relates to a pressure distributor and equalizer for two row cultivators.

Heretofore the beams of two row cultivators have been stabilized by means of springs or by pressure exerted by the feet 15 of the operator on the two inner beams, and by his hands through suitable hand-holds on the two outer beams.

It is the object of my invention to provide means whereby all four beams may be controlled by foot pressure alone thus releasing the operator from the necessity of exerting pressure manually on any of the beams, making the work easier and the results more uniform.

25 A further object of my invention is the provision of a pressure distributor and equalizer for two row cultivators, whereby pressure exerted by the feet is equally distributed to the four beams.

30 Further objects and advantages of my invention reside in the various combinations hereinafter described, as will be apparent as it is better understood by reference to the following specification, when read in connection with the accompanying drawing illustrating the preferred embodiment thereof, in which—

Figure 1 is a view in perspective of a cultivator embodying my invention.

40 Fig. 2 is a detail in perspective of the pivotal connection of the seat beam to the cross beam.

Referring to the drawing 5 indicates an axle, carrying wheels 6 and supporting the frame 7 of the cultivator. The cultivator beams 8 are pivotally supported at their forward ends by pendulum rods 9 depending from a cross bar 10, mounted on brackets 11 which are secured to the frame 7. The 45 cultivator beams 8 are divided into pairs, each pair being connected at their forward ends to an arch 12. The arches 12 are connected at their upper ends to a cross beam 13. A seat beam 14 carrying a seat 15 is 50 supported by an inverted T bolt mounted on the frame 7, above the axle 5. The seat

beam 14 preferably made of two channels, is supported so that it may swing in both vertical and horizontal planes. The forward end of the seat beam 14 is pivotally connected to the cross beam 13. Thus the operator by swinging the seat beam 14 from side to side may shift the cultivator beams laterally.

A rod 17 is connected for pivotal movement in two planes, adjacent the rearward end of each of the cultivator beams 8, and is provided at its upper end with a handhold 18. Adjacent their upper ends the rods 17 are pivotally connected to arms 19 65 70 pivotally mounted on the frame 7, above the axle 5. Similar arms 20 are pivoted concentrically with the arms 19, the upper ends of the arms 19 and 20 being connected by chains 21 and springs 22. Chains 23 and 75 springs 24 connect the upper ends of the arms 20 to the brackets 11, and to a transverse member 25 connecting the brackets 11. Heavy springs 26 are connected to the rods 17 above their pivotal axes and to transverse 80 rods 26^a near the forward ends of the cultivator beams 8. The latter construction is the well known form of "spring lift," its purpose being to lift the cultivator beams 8 to inoperative position when the rods 17 85 are swung forwardly by the operator. All of the foregoing construction is well known in the art and forms no part of my present invention, being described merely to make the application of my invention clear. 90

The two inner cultivator beams 8 are each provided with a stirrup 27 in which the operator places his feet while seated on the seat 15. He may thus exert a downward pressure on the two inner cultivator beams 95 to stabilize and maintain them constantly in the desirable working depth. In order that this pressure may be transmitted to the outer cultivator beams I provide two U bars 28 pivotally mounted on the frame 7 above 100 the axle 5 in suitable bearings 29. The free ends of the U bars 28 adjacent the seat beam 14 are connected by chains 30 to the rods 17 adjacent their lower ends. The other free ends of the U bars 28 are connected by chains 105 31 to the outer rods 17 adjacent their upper ends. Thus when the inner cultivator beams 8 are depressed by the feet of the operator in the stirrups 27 the ends of the U bars 28 are swung downwardly and through the 110 connecting chains 31 and rod 17 the outer cultivator beams 8 are similarly depressed.

The operator is thereby enabled to control and stabilize all four beams by the pressure of his feet, leaving his hands free to drive the team and perform other necessary operations in handling the cultivator. When it is necessary to lift the cultivator beams, the feet are disengaged from the stirrups 27 and the rods 17 swung forwardly by means of the hand-holds to permit the "spring lift" 10 to operate.

From the foregoing it will be readily understood that I have perfected a simple and useful device which makes the work of handling the cultivator much easier because the 15 operator can stabilize the cultivator beams with less exertion through pressure applied by means of the feet. All of the beams being moreover subject to the same degree of pressure, the work is much more uniform than 20 is possible where each of the beams is independently controlled.

My invention involves a relatively slight addition to the construction of two row cultivators as now known, and provides manifest 25 advantages which materially improve the operation of the cultivator.

Various changes may be made in the form, arrangement and construction of the parts, without departing from the spirit and scope of the invention, or sacrificing any of 30 its material advantages, the form hereinbefore described being merely the preferred embodiment thereof.

I claim:

- 35 1. In a two row cultivator, the combination of two pairs of resiliently supported cultivator beams, and means connecting the beams of each pair whereby they are maintained in conjointly movable relation under 40 downwardly directed forces, said connecting means being operative in one direction only whereby the contiguous beams of each pair are freely movable upwardly independent of the other beam of each pair.
- 45 2. In a two row cultivator the combination of a frame, two pairs of cultivator

beams supported thereon, U bars pivotally mounted on said frame, and means connecting the free ends of said U bars to said beams whereby downward pressure exerted 50 by the operator on one of each pair of beams is transmitted to the other beams.

3. In a two row cultivator the combination of a frame, a plurality of cultivator beams supported for vertical movement on 55 said frame, a centrally disposed seat beam, a seat thereon, stirrups on the cultivator beams adjacent said seat beam to receive the feet of the operator and connections between the cultivator beams bearing 60 said stirrups and the remaining cultivator beams whereby downward pressure exerted by the operator is applied uniformly to all of the beams.

4. In a two row cultivator the combination 65 of a frame, two pairs of cultivator beams supported for vertical movement thereon, a centrally disposed seat beam, a seat thereon, means on one of each pair of said cultivator beams to receive the feet 70 of the operator and connections between each pair of beams whereby downward pressure exerted by the operator is applied uniformly to the other beam of each pair.

5. In a two row cultivator the combination 75 of a frame, a plurality of cultivator beams mounted for vertical pivotal movement on said frame, a substantially vertical rod pivotally connected to each of said cultivator beams, a U bar pivoted on said frame, 80 one arm of said U bar being connected to the rod, carried by one of said cultivator beams, adjacent its upper end, while the other arm is connected to the rod, carried by the adjacent cultivator beam, adjacent its 85 lower end, whereby downward pressure exerted on the latter cultivator beam is transmitted to the former.

GEORGE D. HOUSTON.
